[57] CLAIM

The ornamental design for miniature camera, as shown
and described.

DESCRIPTION

FIG. 1 is a perspective view of a miniature camera,
showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a side elevational view thereof; and
FIG. 7 is an elevational view from the opposite side of
FIG. 6.

The broken lines representing the film cartridge are
shown for illustrative purposes only.
